UNITED STATES PATENT OFFICE.

SAMUEL S. FREEMAN, OF OAKLAND, CALIFORNIA; DOROTHY FREEMAN ADMINISTRATRIX OF SAID SAMUEL S. FREEMAN, DECEASED.

NECKTIE.

1,130,587.

Specification of Letters Patent. Patented Mar. 2, 1915.

Application filed December 30, 1913. Serial No. 809,435.

To all whom it may concern:

Be it known that I, SAMUEL S. FREEMAN, a citizen of the United States, residing at Oakland, in the county of Alameda and State of California, have invented certain new and useful Improvements in Neckties, of which the following is a specification.

My invention relates to that class of neckties in which the body, usually termed the silk, is stitched in elongated tubular form and is provided with an inner filling commonly termed the flannel. In neckties of this type, the flannel is either not stitched to the silk at all or is so stitched thereto that it affords no protection against a longitudinal strain or pull on the necktie. The effect of such a strain is to break the stitching of the silk, and to tear the flannel, so that the necktie is practically disorganized and reduced to an unshapely string, with a tendency to twist, rendering it entirely useless.

The object of my invention is to prevent this result, and this I effect by the novel construction of the necktie which I shall now fully describe by reference to the accompanying drawings in which—

Figure 1 is a plan view of the silk from its inner side showing the stitching of the flannel thereto prior to the final seam which converts it into the finished product. Fig. 2 is a plan view from the inner side of the finished necktie. Fig. 3 is a cross section enlarged on line α — α of Fig. 2. Fig. 4 is a fragmentary plan view of the inner side of a necktie showing a modification in the arrangement of the stitching which secures the flannel to the silk.

1 is the body or silk of the necktie. When still unformed, there is stitched to it, on its inner surface and on that side of its median line which, when the silk is converted to tubular shape, forms the inner fold or thickness of the necktie, the filling or flannel 2. The direction of the stitching may be varied though such stitching best extends throughout the length of the flannel.

In Figs. 1 and 2, I show the stitching 3 in a longitudinal course in a straight line. There may be a single line, or, as here shown, a plurality of lines, with a cross stitching 4 at one end and a cross stitching 5 at the other end, said last named cross stitching extending out as shown at 6 to

the edge of the silk. This arrangement presents the constructive advantage of being 55 continuous.

In Fig. 4, I show the stitching 7 which secures the flannel to the silk, as being in a diagonal course from end to end of the flannel, and having end cross stitching 8. 60 When the operation of stitching the flannel to the silk is completed, the silk is turned to tubular form wrong side out, and its two edges, together with the adjacent edge of the flannel, are caught together in a seam, 65 which when the necktie is turned right-side out, presents the finished seam 9 shown in Figs. 2 and 4.

It will be seen that as the flannel is stitched to that portion of the silk which, 70 when the silk is turned to tubular shape, forms the inner fold or thickness of the necktie, and as the final seam 9 is also in this inner side or fold, no stitching or seams are seen on the outer side of the tie, they 75 appearing wholly on the inner side, as is clearly shown in Fig. 3. This result is possible by stitching the flannel to the silk before the latter is converted to tubular form.

The stitches 3 of Figs. 1 and 2 and the 80 stitches 7 of Fig. 4, give such strength to the union of silk and flannel, that the necktie when subjected to longitudinal strain will not break the stitches nor tear the flannel, nor pull out to a string, but will remain 85 flat and in perfect shape throughout its life. To this result the cross stitches 4, 5 and 6 of Figs. 1 and 2, and the cross stitches 8 of Fig. 4 contribute.

I claim:

A necktie comprising a body turned to tubular shape with its longitudinal edges united by a seam, and a filling on the inside of said tubular body, having one of its longitudinal edges incorporated in the seam 95 which unites the edges of the body, said filling being additionally secured to the body by stitches which pass through the inner thickness only of said body.

In testimony whereof I have signed my 100 name to this specification in the presence of two subscribing witnesses.

SAMUEL S. FREEMAN.
